(57) **CLAIM**

The ornamental design for a scaffolding bracket, as shown and described.

DESCRIPTION

FIG. 1 is a front perspective view of the scaffolding bracket; FIG. 2 is a side view of the scaffolding bracket of FIG. 1; and, FIG. 3 is an end view of the scaffolding bracket of FIG. 1.

The objects shown in broken, phantom lines are shown for environmental purposes only and form no part of the claimed design.
